The figure on the drawing is a plan view of a piece of textile fabric bearing my new de-

sign which is intended to be carried forward or repeated ad libitum, as shown. The shading is on the drawing only to indicate more or less contrasting colors and not to indicate specific colors.

The unit of my design is comprised within the arrows shown on the drawings, which arrows form no part of the design.

I claim as my invention:

The ornamental design for a textile fabric or similar article substantially as shown and described.
